No. 36,730.

Patented January 12, 1904.

UNITED STATES PATENT OFFICE.

JOSEPH T. BAILEY, OF PHILADELPHIA, PENNSYLVANIA, ASSIGNOR TO BAILEY, BANKS & BIDDLE COMPANY, A CORPORATION OF PENNSYLVANIA.

DESIGN FOR A BADGE.

SPECIFICATION forming part of Design No. 36,730, dated January 12, 1904.

Application filed December 9, 1903. Serial No. 184,490. Term of patent 14 years.

To all whom it may concern:

Be it known that I, JOSEPH T. BAILEY, a citizen of the United States, residing in the city and county of Philadelphia, State of Pennsylvania, have invented a new, original, and ornamental Design for a Badge, reference being had to the accompanying drawing, which fully illustrates the same.

What I claim as new, and desire to secure by Letters Patent, is—

The ornamental design for a badge substantially as shown.

JOSEPH T. BAILEY.
